UNITED STATES PATENT OFFICE.

GEORGE F. KEARNEY, OF HIGHLAND PARK, MICHIGAN.

PAPER-ROLL HOLDER.

1,109,929.

Specification of Letters Patent. Patented Sept. 8, 1914.

Application filed January 6, 1913. Serial No. 740,382.

To all whom it may concern:

Be it known that I, GEORGE F. KEARNEY, a citizen of the United States, residing at Highland Park, county of Wayne, State of Michigan, have invented a certain new and useful Improvement in Paper-Roll Holders, and declare the following to be a full, clear, and exact description of the same, such as will enable others skilled in the art 10 to which it pertains to make and use the same, reference being had to the accompanying drawings, which form a part of this specification.

This invention relates to paper roll holders and its object is a simple and inexpensive device for the retaining rolls of toilet paper and other similar rolls in which the paper is in a continuous length and preferably perforated at regular intervals whereby 15 the portion desired for use may be readily separated from the roll, the parts being so arranged as to prevent the withdrawing or unwinding of more than a single sheet at each actuation of the device. In holders 20 ordinarily in use for this purpose, it is possible to unwind a greater portion than is required at any one interval as no provision is made to prevent a continued rotation of the roll after a specified portion has been 25 unwound therefrom, and it is the purpose of the invention herein disclosed to overcome such fault and to provide a device from which the roll may not be removed until the paper is entirely unwound there- 30 from, and in which the working parts such as springs and the lock for the spindle, hereinafter more fully described, are wholly inclosed within the core or spindle upon which the roll is mounted and, therefore, in such 35 position as to prevent disarrangement or displacement thereof by accident or intent.

A further object of the invention is a device of the nature stated in which rolls provided with a core of peculiar formation 40 only are adapted for use on the device thereby limiting the device to the use with such rolls and preventing a substitution of rolls of other forms.

These and further objects and novelties of 50 the invention are hereinafter more fully de-

scribed and claimed and shown in the accompanying drawings in which—

Figure 1 is a perspective view of my improved paper roll holder. Fig. 2 is a sectional view of the paper roll and spindle 55 illustrating more fully the structure thereof and method of mounting in the supporting bracket. Fig. 3 is a cross-section of the spindle on line $\alpha-\alpha$ of Fig. 2.

Similar characters refer to similar parts 60 throughout the drawings and specification.

The device consists of a bracket 1 having a fixed arm 2 and a hinged arm 3, and fixedly secured to the arm 2 is a shaft 4. On the shaft 4 is a pyramidal shaped core or 65 spindle 5 having a central bore for the shaft, the portion 6 of said bore being greater in diameter than the portion 7, thus providing a seat 8 for a thrust bearing 9 on the shaft 4. The shaft is formed with a 70 main portion 10 of greater diameter than the portion 11 upon which the thrust bearing is mounted, and the enlarged portion 10 is provided with a spiral groove 12 in which a pin 13 secured to the core rides, 75 whereby a rotation of the core produces a longitudinal movement thereof on the shaft as indicated by the dotted lines α in Fig. 2. This longitudinal movement compresses a 80 spring 14 on the part 11 of the shaft between the thrust bearing 9 and the enlarged portion 10 of the shaft. The thrust bearing 9 enables the core to be rotated without a rotation of the spring on the shaft and prevents friction which would otherwise occur if the spring engaged a rotating seat. 85

The hinged arm 3 terminates in an enlarged portion 15 provided with a socket 16 in which the free end of the portion 11 of the shaft engages, and in the portion 15 of 90 the arm 3 is secured a pin 17 provided with a longitudinal slot 18 in which a pin 19 in the arm engages and by means of which the pin is held from complete withdrawal from the end of the arm. The end of the portion 95 11 of the shaft is bored to receive the pin 17 and, when fully inserted within the bore in the shaft, a lock-pin 191 engages in the slot and holds the pin in position. The pin 191 is provided with a spring 20 more particu- 100

larly shown in Fig. 3 which tends to hold the pin in place and provides a lock for holding the parts in normal position. The core 5 is provided with a cut out portion 21 5 allowing access to the lock-pin 191 to withdraw it from engagement with the slot 18 whereupon the pin 17 may be withdrawn from the end of the shaft as indicated in dotted lines in Fig. 2, and whereupon the 10 hinged arm 3 may be swung to one side as indicated by the dotted arrow in said figure. The paper core of the roll may now be removed from the core or spindle 5 and a new roll placed thereon, whereupon the arm and 15 pin 17 are returned to their normal position as shown by full lines in said figure. From the above description it may be seen that all loose parts such as the spring etc., as well as the locking device are entirely inclosed with- 20 in the core or spindle 5 and therefore in such position that mischievously inclined persons may not readily disarrange the parts and destroy the usefulness of the device.

25 The paper preferably used on this device is perforated at regular intervals of greater or less extent depending upon the purpose for which the roll to be used and the longitudinal movement of the roll on the 30 shaft is sufficient to allow removal of a single sheet at each actuation thereof, the longitudinal travel of the roll being such that a sheet may be unwound from the roll when the core is of its smallest diameter 35 and, while a somewhat greater length may be unwound from the roll at a single actuation when first placed thereon, it is not so great as to allow the removal of two complete sheets. The sudden stopping of the 40 roll in its longitudinal movement on the shaft, tends to separate the sheet from the roll at the line of perforation.

Fixtures of this nature are not ordinarily sold to the consumers but remain the property of those supplying the paper, the intent being to secure succeeding orders from the consumer by reason of the provision of the fixture. This method of disposing of the fixtures does not always hold the paper 50 supply business as it is very common for manufacturers to supply rolls of paper for use on fixtures belonging to or furnished by other supply houses and it is an object of this invention to provide a core or spindle 55 of such shape that a roll of paper in order to be used on this fixture must have a core of corresponding shape, and rolls not as provided can not operate the device. I have therefore formed the spindle 5 in the shape 60 of a four sided truncated pyramid and within the usual round core 22 of the paper roll, I provide a paper core 23 corresponding in shape to the shape of the spindle 5 and provided with the ends 24 and 25 which

are glued in place in the paper core of the 65 roll. With a core of this form fitting the spindle, a rotation of the roll insures a rotation of the core and consequent movement of the spindle is heretofore described, but if a roll of the ordinary round core 70 only be placed on the spindle the axis of the roll will not coincide with the axis of the shaft but will lay at such an angle thereto that the edge of the roll will engage the sharp teeth like projection 26 on the arm 75 3 and a rotation of a roll be practically prevented and therefore such roll would be totally unadapted for use on the fixture. Consequently consumers that are supplied with fixtures having the formation herein 80 described must necessarily seek their supply paper from the manufacturer or agency supplying the fixture.

Having thus briefly described my invention and its mode of operation, what I claim 85 and desire to secure by Letters Patent of the United States is—

1. In a paper roll holder, a bracket, a shaft secured thereto, a roll supporting spindle carried thereby, means whereby a 90 rotation of the spindle produces a longitudinal movement thereof, and a spring adapted to yieldably resist said movement and return the spindle to its original position upon the release thereof. 95

2. In a paper roll holder, a bracket, a shaft fixedly secured thereto, a paper roll spindle carried by the shaft, means whereby rotation of the roll and spindle produces a longitudinal movement thereof, and a 100 spring within the spindle adapted to yieldably resist said longitudinal movement and return the spindle to its original position upon the release thereof, the arrangement of parts being such that the longitudinal 105 movement of the spindle is limited.

3. In a paper roll holder, a bracket, a shaft fixedly secured thereto, a paper roll spindle rotatably mounted on the shaft, said shaft being provided with a spiral groove, 110 a pin or lug on the spindle engaging said groove whereby a rotation of the spindle produces a movement thereof longitudinally of the shaft, and a spring adapted to yieldably resist said longitudinal movement and return the spindle to its original position 115 when released.

4. In a paper roll holder, a bracket provided with a fixed and a movable arm, a shaft having one end secured to the fixed arm the movable arm being provided with a socket for supporting the free end of the shaft, a paper roll spindle mounted for rotation on the shaft, means whereby a rotation of the spindle produces a longitudinal movement thereof, a spring adapted 120 to yieldably resist said longitudinal movement and return the spindle to its original 125

position when released, and releasable means for holding the movable arm in engagement with the shaft end.

5. In a paper roll holder, a bracket provided with a fixed and a pivoted arm, a shaft having one end secured to the fixed arm, the opposite end being normally supported by the pivoted arm, a paper roll spindle mounted for rotation on the shaft, 10 said shaft being provided with a spiral groove, a lug or pin on the spindle engaging in said groove whereby a rotation of the spindle produces a movement thereof longitudinally of the shaft, a spring adapted to yieldably resist said longitudinal movement and return the spindle to its original 15 position when free to act, and releasable means for holding the pivoted arm in normal engagement with the shaft end.
- 20 6. In a paper roll holder, a bracket provided with a fixed and a pivoted arm, a shaft having one end secured to the fixed arm, the opposite end being normally supported by the pivoted arm, a pin carried 25 by the pivoted arm and normally engaging in a bore provided therefor in the shaft end, released means adapted to hold the pin in the bore, a paper roll spindle mounted for rotation on the shaft, and covering said 30 pin holding means, means whereby a rotation of the spindle produces a movement thereof longitudinally of the shaft, and a spring within the spindle adapted to yieldably resist said longitudinal movement and 35 return the spindle to its original position when released.

7. In a paper roll holder, in combination, 40 a bracket provided with a fixed and a movable arm, a shaft having one end secured to the fixed arm, the opposite end being normally supported by the movable arm, a tapered spindle mounted for rotation on the shaft adapted to support a paper roll, releasable means for holding the movable arm 45 in its normal position, the small end of the spindle being adjacent to the movable arm, means for holding the paper roll with its longitudinal axis substantially in coincidence with the longitudinal axis of the shaft. 50

55 8. In a paper roll holding device, in combination, a bracket or support, a rotatable, tapered, spindle carried thereby adapted to support a paper roll, a tapered core for said paper roll adapted to hold the roll with its longitudinal axis substantially in coincidence with the longitudinal axis of the spindle. 60

9. In a paper roll holding device, in com-

bination, a bracket or support, a rotatable 65 spindle carried thereby adapted to support a paper roll a core for said paper roll adapted to hold the roll with its longitudinal axis substantially in coincidence with the longitudinal axis of the spindle, and 70 means adapted to prevent a rotation of the roll when the axis thereof is out of coincidence with the axis of the spindle.

10. In a paper roll holding device, in combination, a bracket or support, a rotatable 75 spindle carried thereby, adapted to support a paper roll, means for holding the roll with its longitudinal axis substantially in coincidence with the longitudinal axis of the spindle, and means adapted to prevent a rotation of the roll when the said axis thereof is out of coincidence with the said axis of the spindle.

11. In a holder for paper rolls formed of a sheet of paper perforated at substantially 85 regular intervals in parallel lines crosswise of the sheet, in combination, a bracket, a paper roll support carried thereby, a paper roll supporting spindle rotatable on the support, and means controlling the rotation of 90 the roll spindle whereby a portion only of the sheet substantially equal in length to the distance between perforations therein may be unwound at a single actuation thereof, said rotation controlling means being automatic in action for successive operations. 95

12. In a paper roll holder, a bracket, a support for a paper roll carried thereby, a paper roll spindle on said support, means whereby a rotation of the paper roll spindle 100 produces a longitudinal movement thereof on its support, and a spring adapted to resist said movement and return the roll spindle to its original position when free to move. 105

13. In a paper roll holder, a bracket, a support for a paper roll carried by the bracket, the paper roll being rotatable to and movable longitudinally of the support, the longitudinal movement of the roll being 110 limited whereby the rotation of the roll is also limited, and means for repositioning the roll for successive operations.

14. In apparatus of the class described, the combination with a bracket of a support 115 for paper rolls, a paper roll spindle on the support, a spiral groove formed in one of said elements and a lug carried by the other of said elements engaging said groove whereby a rotation of the spindle causes a 120 movement of one of the elements longitudinally of the other, and yieldable means resisting said movement adapted to restore the parts to their original relation.

15. In a paper roll holder, a bracket, a 125 paper roll support carried thereby, a non-cylindrical spindle rotatable on and movable longitudinally of the support, a cylin-

drical core for the roll, means carried by the core and adapted to fit over the spindle whereby a rotation of the roll and core produces a rotation of the spindle, and means whereby a rotation of the spindle causes a longitudinal movement thereof limiting the extent of rotation of the roll.

In testimony whereof I sign this specification in the presence of two witnesses.

GEORGE F. KEARNEY.
